(57) **CLAIM**

What is claimed is the ornamental design for a fishing hook eyelet, as shown and described.

DESCRIPTION

FIG. 1 is a perspective view of a first embodiment of a fishing hook eyelet, showing the new design;

FIG. 2 is a front elevational view thereof, the rear elevational view being a mirror image thereof;

FIG. 3 is a right-side elevational view thereof;

FIG. 4 is a left-side elevational view thereof;

FIG. 5 is a top plan view thereof;

FIG. 6 is a bottom plan view thereof;

FIG. 7 is a perspective view of a second embodiment thereof;

FIG. 8 is a front elevational view thereof, the rear elevational view being a mirror image thereof;

FIG. 9 is a right-side elevational view thereof;

FIG. 10 is a left-side elevational view thereof;

FIG. 11 is a top plan view thereof; and,

FIG. 12 is a bottom plan view thereof.

The broken lines showing a fish hook in the figures are environmental matter, and form no part of the claimed design.
